FIG. 6.

FIG. 8.

A technical diagram of a double-leaf door. The door is shown in an open position, revealing a central vertical panel and two side panels. The left side panel is labeled '18' with an arrow. The central panel has a dashed horizontal line near the top. The right side panel is labeled '15' with an arrow. The door is marked with several numbers: '12' is on the top left leaf, '11' is on the top right leaf, '13' is on the top right leaf, '10' is on both the left and right side panels, '8' is on the left side panel, '9' is on the right side panel, and '16' is on the right side panel. The bottom of the door features a decorative base with diagonal hatching.

FIELD STRETCHER

Francis E. Montgomery, Washington, D. C.

Application June 24, 1942, Serial No. 448,296

3 Claims. (Cl. 5—82)

My present invention relates to an improved field stretcher of the folding type, which is also adapted for use as an invalid lift and transfer, a portable litter, or as a collapsible cot; but for convenience of description I shall herein refer to the implement as a field stretcher, or as a stretcher.

The primary object of the invention is the provision of a field stretcher which is comparatively light in weight, simple in construction, and which may with convenience and facility be folded to compact form and shape for storage and portability, and which may with equal facility be unfolded and extended for use when required. In carrying out my invention I employ a minimum number of parts in order that the stretcher may be manufactured at comparatively low cost of production, and its parts assembled with convenience, to produce a rugged, well-braced, and strong implement for the performance of its functions.

I utilize a pair of longitudinally extending side-bars each comprising two hinged sections with means for retaining them in alined, extended position, and means are also provided to prevent relative movement or twisting of the alined sections at the hinged joint. The side bars are spaced apart and pivotally connected by a pair of transversely extending, foldable, braces having means for retaining them in extended position. The stretcher is also provided with a suitable number of fixed legs and feet for use in supporting the implement when in extended position, and each leg is mounted on a side-bar section in such manner as to frictionally engage another section when the stretcher is folded into compact form, in order to hold or retain the sections and cover in close relationship to provide a package or bundle that is convenient for storage or handling.

The invention consists in certain novel combinations and arrangements of parts for accomplishing the above purposes as will hereinafter be more fully set forth. In the accompanying drawings I have illustrated one complete example of the physical embodiment of my invention wherein the parts are combined and arranged according to one mode I have devised for the application of the principles of my invention, but it will be understood that changes and alterations may be made in the exemplifying structures of the drawings, within the scope of my appended claims, without departing from the principles of my invention.

Figure 1 is a top plan view of the field stretcher

embodiment my invention, shown in extended position, the flexible cover being indicated by dotted lines for convenience of illustration.

Figure 2 is a side view of the stretcher in Figure 1.

Figure 3 is a side view of the stretcher in folded position; and Figure 4 is a top plan view of the same.

Figure 5 is an enlarged detail sectional view, as at line 5—5 of Figure 3, showing the functions of the legs in retaining the sections in folded position.

Figure 6 is an enlarged detail perspective view illustrating the folded hinge joint between two side-bar sections.

Figure 7 is a detail sectional view of the hinge unit.

Figure 8 is a detail perspective view of part of the folded stretcher, showing the handle ends of 20 the four side-bar sections, together with one of the folded transverse braces, and the fixed legs for retaining the sections.

For convenience of illustration, the cover C is indicated by dotted lines in Figure 1, and this cover, which is fashioned of suitable flexible material is fastened in appropriate length along the outer edges or side faces of the side bars. The cover, as usual, has ample material to provide a comfortable support for a patient or invalid and the material possesses adequate flexibility to permit folding and unfolding complementary to the manipulations of the foldable side bars of the stretcher.

Each of the two longitudinally extending side-bars comprises two sections as 1, 1a and 2, 2a, having handles 3 at their outer ends and each pair of sections is provided with a pivotal joint or hinge unit which are indicated each as a whole by the numerals 4 and 5, in the assembly views of the drawings. These hinge units are of complementary or duplicate construction, and therefore a description of one unit or joint, as in Figures 6 and 7, will suffice for both units.

In this illustrated embodiment of my invention, where the side-bar sections are preferably fashioned of wood to insure light weight, the abutting squared ends of the sections are first fashioned with slots of sufficient depth to accommodate two complementary flat metal plates 8 and 9, rigidly fastened as by screws 10 within the slotted ends of the sections.

These parallel flat hinge-plates are pivoted together by means of a hinge pin or pivot pin 11 so that one of the sections may be swung or rotated on the pin relatively to the other section

through an arc of one hundred and eighty degrees. Thus the hinged, sectional side bar may be folded upon itself, to bring the sections of the bar into approximately parallel relation, and the folded bar may be unfolded to extend the sections in alinement.

Each of the two hinge plates 8 and 9 is fashioned with a brace-head, as 12 and 13, which project beyond the abutting ends of the sections and also beyond the hinge pin; and to accommodate the two projecting braces or heads the inner adjoining ends of the sections are slotted as at 14, so that these heads are guided by and swing into the slots when the sections are swung into alinement for extending the stretcher. In this manner the hinge unit or joint is reinforced to prevent any tendency of the joint to twist or wobble, and a stable arrangement of parts is provided to withstand carefree handling of the implement in the folding and unfolding operations.

This combination of the two hinge plates and reinforcement of the joint permits the hinge pin to be offset between two adjoining corners of the abutting ends of the sections, and this location of the pivot, in turn, permits facile infolding of the sections to approximate parallel relation, thus insuring a compact bundle or package when the stretcher is folded that occupies a small space for storage, and also provides a convenient bundle or package for handling as in transportation.

To hold the joint of the extended side bar against sagging under the weight of the load of a patient, with the wooden sections, I provide an overlapping metal top plate 15 secured as by screws 16 to one of the sections, and the projecting end 17 of this plate forms a bridge-lug that projects across the joint and the pivot pin between the sections, and overlaps a portion of the abutting end of the other section. The overlapped section is fashioned with a top recess or groove as 18 into which the overlapping lug fits to provide a continuous smooth upper face for the extended side bar.

When the stretcher is in extended position, the parallel side bars are spread or spaced apart a suitable distance by means of two transversely extending, folding braces, one brace located at each handle end of the stretcher, and the outer ends of the links of the folding braces are pivotally connected to the side bars.

These duplicate braces, in Figure 1, are indicated as a whole by the numerals 19 and 20, and each brace includes a pair of links 21, 22, pivoted together at 23 with their outer ends pivoted at 24 to an angle bracket 25 fastened to a side bar section. The braces are adapted to fold inwardly, the links swinging through an arc of approximately ninety degrees toward the center joints of the stretcher, and the braces are prevented from swinging outwardly from alinement by means of a hook 26 on one of the links. This hook projects beyond the center pivot of the brace and is rigid with one link so that it may enclose or overlap a portion of the other link, as best seen in Figure 1 to prevent outward swing of the links. The hook clamps tightly with a close fit on the upper and lower faces of the link, and the friction between the inner faces of the hook and the upper and lower faces of the link holds the joint against breaking until or unless force is applied to the links for that purpose.

As shown, the extended stretcher may be supported above the ground or floor by means of a suitable number of legs, here shown as six, all

provided with feet, and arranged in pairs, one pair at each of the handle ends of the stretcher, and another pair adjacent the central hinge joints of the stretcher. The legs 27, 28, 29, for one side of the stretcher, and the complementary legs 30, 31, and 32 for the other side of the stretcher, each have a foot portion 33, and the legs are all fixed to or fastened on the side bars, as by screws 34.

The legs in the opposed pairs 27-30, 28-31, and 29-32 are staggered in their relative positions, in order that in addition to the performance of their functions as supports for the extended stretcher, they may also be utilized as guides and retainers for guiding and holding the sidebar sections in compact arrangement when the stretcher is folded upon itself.

One convenient way for folding the stretcher upon itself is first to up-end it from horizontal position to upright position and stand it upon two of the handle ends of the side bars. Then the upper transverse brace may be infolded by hand, while the lower transverse brace is "kicked" or infolded by pressure from a foot. The upper half of the stretcher is then folded inwardly as the folding side bars are carried toward each other, the cover C of course is automatically folded and its folds conform to the changing shape of the stretcher. This lateral movement of the side bar sections and infolding movement of the stretcher brings the four side bar sections into closely associated parallelism with the folded stretcher standing on the four handle-ends of the stretcher.

As the four sections of the side bars are thus brought into closely arranged parallelism, the free ends of the legs (as 27, 29 and 30, 32) of one bar-section slide across and in frictional contact with the outer flat face of its complementary, hinged section. Thus the two sections of each folded side bar, near the handle ends are guided to position and held at their outer sides by a leg, and these two sections at their jointed ends are held or braced by the heads of the hinge plates. The handle ends of the two sections of each folded side bar are also held by friction against separation except by force. Inasmuch as the cover C encloses the outer side or face of the side bar, which is flat, or flattened to provide coaction with the inner flat side of the leg, the presence of the cover enhances the frictional engagement between the metal leg and the flat fabric-covered outer face or side of the side-bar.

The two central legs 28 and 31 attached at the inner flat sides of the side-bar sections 1a and 2a, are also arranged in staggered relation, so that the outer side of the leg 28 guides and slides in frictional contact with the inner flat side of section 1, when the stretcher is folded, and the outer side of the leg 31 guides and slides in frictional contact with the inner side of the section 2.

The angle brackets 25, 25, may also be staggered in their fixed relative positions on the inner sides of the sections to which they are attached in order that the handle-ends of the sections 1-2 and 1a-2a may be squeezed together as closely as possible in compacting the folded parts.

No attempt has been made to show the folds that occur in the flexible cover C when the stretcher is folded, as it is obvious these folds may assume various shapes and lines under different folding operations. However, the flexible cover C invariably folds upon itself at its transverse center line when the stretcher frame or side

bars are folded, and then the natural folds of the cover are wrapped about the four side-bar sections to aid in forming the compact bundle.

Various changes and alterations may be made in the structures illustrated in the accompanying drawings, as for instance the squared abutting hinged ends of some of the side-bar sections may be provided with wear plates as 35, made of metal or other suitable material, especially when the side-bar sections are fashioned of wood. These and other similar changes and alterations are contemplated in the manufacture of and physical embodiment of my invention.

The folded stretcher, with its cover utilized as a wrapper may be compacted into a comparatively small space for enclosure in a packing-box or kit-box, and the bundle thereby becomes part of an emergency equipment adapted for various uses.

Having thus fully described my invention, what I claim as new and desire to secure by Letters Patent is:

1. The combination in an infolding stretcher including two pairs of aligned, hinged side-bar sections and spaced foldable links pivotally connecting parallel sections, a flexible cover mounted on the side bars, staggered legs arranged in opposed pairs and rigidly mounted at the outer sides of and adjacent the free ends of the sec-

tions, and each of said legs adapted to frictionally engage and retain an adjoining section when the stretcher is in folded position.

2. The combination in a folding stretcher having parallel side bars each including aligned sections having hinge plates and a hinge pin connecting the plates and offset from adjoining corners of the section-ends, each said plate having an integral projecting head in a plane at right angles to the axis of the hinge pin for holding the aligned sections against twisting movement, said section-ends having recesses to receive said heads, and means at each hinge joint to prevent transverse depression of the section-joints.

3. The combination in a folding stretcher having parallel side bars each including two aligned sections each section having a hinge-plate and a hinge pin connecting the plates and offset from two adjoining corners of the section-ends, each said plate having a projecting head in a plane at right angles to the axis of the hinge pin and said section-ends having recesses to receive said heads whereby twisting movement of the hinge joints is prevented, and one hinged end of each bar having an upper rigid projection overlapping its complementary aligned section to prevent transverse depression of the section-joints.

FRANCIS E. MONTGOMERY.
